PIVOTAL BRACED PROTECTOR AND KNEE GUARD

Daniel Bednarczuk, 153-15 89th Ave., Jamaica, N.Y.
11432, and Arnold T. Milton, 7 Olmsted Road, Scars-
dale, N.Y. 10583

Filed Oct. 11, 1974, Ser. No. 514,061

Term of patent 14 years

Int. Cl. D2—02; D24—04
U.S. CL. D83—1 J

FIG.2

FIG.1

FIG.3

FIG.4

FIG.5

FIG.6

FIG. 1 is a side elevational view of a pivotal braced protector and knee guard, showing our new design;

FIG. 2 is a front elevational view of the device;

FIG. 3 is a horizontal sectional view taken along line 3-3 of FIG. 1;

FIG. 4 is a rear elevational view thereof;

FIG. 5 is a sectional elevational view taken along line 5-5 of FIG. 2;

FIG. 6 is a side elevational view of the device in full knee bend position.

We claim:

The ornamental design for a pivotal braced protector and knee guard, as shown and described.
